UNITED STATES PATENT OFFICE.

GEORGE A. BULL AND CASE E. LONES, OF BUCYRUS, OHIO.

DOOR-CHECK.

1,179,606.

Specification of Letters Patent. Patented Apr. 18, 1916.

Application filed June 14, 1915. Serial No. 33,969.

To all whom it may concern:

Be it known that we, GEORGE A. BULL and CASE E. LONES, citizens of the United States, residing at Bucyrus, in the county 5 of Crawford and State of Ohio, have invented certain new and useful Improvements in Door-Checks, of which the following is a specification.

This invention relates to improvements in 10 devices for checking doors and holding them open or partly open, and has for one of its objects to improve the construction and increase the efficiency and utility of devices of this character.

Another object of the invention is to provide a simply constructed device which may be attached to doors of various forms and sizes without material structural change either in the door or in the improved 20 device.

Another object of the invention is to provide a simply constructed device which automatically adapts itself to uneven floors or inclined floors.

With these and other objects in view, the invention consists in certain novel features of construction as hereafter shown and described and then specifically pointed out in the claims; and in the drawings illustrative 30 of the preferred embodiment of the invention. Figure 1 is a sectional elevation of the device from the front; Fig. 2 is a sectional elevation of the device from one side; Fig. 3 is a transverse section on the line 35 3—3 of Fig. 2; Fig. 4 is a view similar to Fig. 1, illustrating a modification in the construction; Fig. 5 is a transverse section on the line 5—5 of Fig. 4; Fig. 6 is a view similar to Figs. 1 and 4, illustrating another 40 modification in the construction; Fig. 7 is a transverse section on the line 7—7 of Fig. 6.

Corresponding and like parts are referred to in the following description and indicated in all the views of the accompanying drawings by the same reference characters.

The improved device comprises a cylindrical shell 10 having a detachable top and perforated brackets 11 by which the device 50 is secured to a door, a portion of which is indicated conventionally at 12.

The shell is provided with a transverse support 13 for a vertically movable bolt 14. The support may be imperforate, as shown 55 in Figs. 1 and 2 or in spider-like form, as

shown in Figs. 4 to 7 inclusive. The bolt 14 may be of any required form, either circular, as indicated in Fig. 3 with a longitudinal guide rib 15 operating in a corresponding guideway in the support 13, or square as shown in Figs. 4, 5, 6 and 7, or other form than round, to prevent the rotation of the bolt, while at the same time permitting it to freely move vertically of the casing. Connected to or formed integral with the lower end of the bolt 14, is a plunger like member 16, which may be cylindrical in form, as shown in Figs. 1, 2 and 3 or in the form of a plate or disk, as shown in Figs. 4 and 6.

In the construction shown in Figs. 1 and 2, the plunger 16 is provided with a depending ear 17, and mounted to swing by a pivot 18 is a supporting wheel 19. By this means, the support 19 is free to swing laterally to a certain extent, and is limited in its movement by the angular upper form of the support 19, as represented at 20. By this means, the support 19, together with the caster wheel 21, is free to swing into 80 the position shown by dotted lines in Fig. 1, so that the caster wheel automatically adapts itself to the uneven portions of a floor or to an inclined floor, indicated at 22.

In the construction illustrated in Figs. 4 and 6 the member 16 is provided with rigid ears 23 spaced apart and between which the caster wheel 21 is rotatably mounted.

In the construction shown in Figs. 2 and 3, a longitudinal guideway 24 projects from the shell 10 at one side and communicates at 25 at its upper portion with the interior of the shell and is provided at its lower portion with a downwardly opening slot 26, the guideway 24 having a stop notch or recess 27. Slidably disposed within the guideway 24, is a plunger 28 from which an ear 29 extends through the slot 26. Pivoted at 30, upon the ear 29, is a stop device 31 having a flat upper face and supported yieldably in position relative to the ear 30 by a spring 32. A relatively large spring 33 is disposed around the bolt 14 between the stop member 13 and the plunger member 16, and operates to maintain the bolt and the caster 105 wheel yieldably in projected position, as illustrated in Figs. 1 and 2. A pull member, in the form of a cable 34, is connected, respectively, to the bolt 14 and to the plunger 28 and runs over a guide pulley 35 110

mounted for rotation upon a transverse pin 36, the latter supported in the shell 10 in any suitable manner.

The bolt 14 is provided with a longitudinal cleft in its upper end to receive a perforated plate 37 and secured in position by a cotter pin 38. One end of the cable 34 is connected to the plate 37, while the opposite end of the cable extends through a longitudinal aperture in the plunger 28 and is secured in position by knotting the lower end of the cable, as illustrated in Fig. 2. The cable 34 is of sufficient length to cause the caster wheel 21 to be withdrawn from engagement with the floor, represented conventionally at 39, when the inner edge of the stop member 31 has been depressed to a sufficient extent to engage in the notch 27. By this arrangement, when the member 31 is released from engagement with the notch 27, the spring 33 will project the caster wheel 21 into engagement with the floor and thus hold the door in whatever position it may be placed, and when the door is to be released, the member 31 is forced downwardly until its inner edge engages in the notch 27, this movement elevating the plunger 14 and the caster wheel connected therewith against the resistance of the spring 33 and thus withdrawing the caster wheel from engagement with the floor. The spring 32 operates to force the inner edge of the member 31 into the notch 27 when the member 31 is depressed.

In Figs. 4 and 5, a slight modification of the construction is shown consisting in dispensing with the projecting guideway 24 and employing a member 40 slightly different in construction from the member 29, but producing the same results. The member 40 projects through a longitudinal slot 41 in the shell 10 and is provided with spaced ears 42 at its inner end within the shell, and pivoted at 43, between the ears 42, is a flexible member 44, preferably in the form of a flat chain, as shown. The plunger 14 in the modification shown in Figs. 4 and 5 is square, as before stated, and is provided with a longitudinal cleft in its upper end in which a plate 45, corresponding to the member 37, and to which the opposite end of the flexible member 44 is connected, the member 45 being secured in position by a cotter pin 46 which corresponds to the cotter pin 38. The flexible member 44 leads over a guide pulley 47 mounted for rotation upon a pin 48 extending through the shell; the members 47-48 corresponding to the members 35 and 36. Pivoted at 49 to the member 40, externally of the shell, is a movable member 50, corresponding to the member 31, and adapted to engage in a

notch 51 in the shell when depressed. The operation of the member 50 is precisely the same as the member 31, before described, and when depressed will elevate the bolt 14 and the caster wheel 21 carried thereby against the resistance of the spring 33 and hold the caster wheel in elevated position when the member 50 engages automatically in the notch 51.

In Fig. 6, another slight modification in the construction is shown, consisting in forming the bolt 14 with a transverse slot 52 near its upper end and pivoting a lever 53, at 75 54, with the longer end of the lever extending through the slot and the shorter end connected by a flexible member, such as a chain 55, to the member 40, the remaining parts being substantially the same as shown in 80 Figs. 4 and 5.

The form of plunger shown in Figs. 1 and 2, as before stated, is used where the floor is uneven or inclined, while the form of plunger shown in Figs. 4 and 6 will be 85 used where the floor is level.

Having thus described the invention, what is claimed as new is:

1. In a device of the class described, a tubular support adapted to be attached to a door, a spring pressed plunger within the support, and a frame carrying a supporting wheel and mounted to swing laterally relative to said plunger, whereby the supporting wheel is caused to automatically conform to unevenness of surface.

2. In a device of the class described, a tubular support adapted to be attached to a door, a spring pressed plunger within the support and having a downwardly directed ear, and a frame carrying a supporting wheel and including sides spaced apart and pivoted by the spaced sides to said ear, the upper terminals of said ears being reversely inclined to limit the lateral movement of the frame, whereby the supporting wheel is caused to automatically conform to unevenness of surface.

3. In a device of the class described, a tubular support having a longitudinal guideway and adapted to be attached to a door, a spring pressed plunger operating within said support and carrying a supporting wheel, a member slidable in said guideway, a guide pulley, and a flexible member connected at one end to said slidable member and operatively connected at the other end to said plunger and leading over said guide pulley.

In testimony whereof we affix our signatures.

GEORGE A. BULL. [L.S.]
CASE E. LONES. [L.S.]
